CLAIM

The ornamental design for a toy handbag, as shown and described.

DESCRIPTION

FIG. 1 is a front, right and bottom perspective view of a toy handbag, showing my new design;

FIG. 2 is a rear, left and top perspective view thereof;

FIG. 3 is a perspective view thereof, shown in an open condition;

FIG. 4 is a front view of the toy handbag shown in the closed condition of FIG. 1;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines shown in the drawings illustrate portions of the toy handbag that form no part of the claimed design.
